SPORTS DISPLAY CORNICE UNIT

Wallace M. Goodstein, San Francisco, Calif.

Application February 18, 1952, Serial No. 18,571

Term of patent 14 years

(Cl. D21—1)

To all whom it may concern:

Be it known that I, Wallace M. Goodstein, a citizen of the United States and a resident of the city and county of San Francisco, State of California, have invented a new, original, and ornamental Design for a Sports Display Cornice Unit, of which the following is a specification, reference being had to the accompanying drawings forming a part hereof.

Fig. 1 is a front perspective view of a sports display cornice unit, showing my new design.

Fig. 2 is a rear elevational view thereof.

A plurality of L-shaped brackets are secured to the rear of the unit adjacent to its upper edge for removably mounting the unit on a cornice.

I claim:

The ornamental design for a sports display cornice unit, as shown.

WALLACE M. GOODSTEIN.
